(57) **CLAIM**

I claim the ornamental design for an inflatable object for recreational use, as shown and described.

DESCRIPTION

FIG. 1 is a top plan view of an inflatable object for recreational use according to the present design;

FIG. 2 is a bottom plan view of the inflatable object for recreational use of FIG. 1;

FIG. 3 is an end view of the inflatable object for recreational use of FIG. 1;

FIG. 4 is an end view of the inflatable object for recreational use showing the end opposite of FIG. 3;

FIG. 5 is a side view of the inflatable object for recreational use of FIG. 1; and,

FIG. 6 is a view of the side of the inflatable object for recreational use of FIG. 1 opposite the side depicted in FIG. 5.

The broken lines appearing in FIGS. 1 and 2 form no part of the claimed design, but rather are for illustrative purposes only.
